PROCESS AND APPARATUS FOR TANNING LEATHER

Filed Jan. 13, 1930

Inventor:

Rene Chavand

By *Louis Vauvigne*
Attorney.

UNITED STATES PATENT OFFICE

RENÉ CHAVAND, OF LYON, FRANCE

PROCESS AND APPARATUS FOR TANNING LEATHER

Application filed January 13, 1930, Serial No. 420,536, and in France January 12, 1929.

My invention relates to a process of tanning leather for the manufacture of belts and to an apparatus for carrying out said process. It has for its object to produce belts which do not grow longer at use whilst being highly elastic.

It has been proposed to tan leather whilst under tension, the hides being tensioned, before tanning, on suitable frames which are then immersed into the tanning bath. In this process, the hides are suddenly stretched the fibers are abnormally stressed and the leather obtained is practically inelastic which is a most serious drawback in the belt industry.

According to my invention, the hides are tensioned progressively during the tanning operation.

The apparatus employed comprises a stretching frame driven by a screw with rotating nut, and a speed-reducing set adjusted in such a way that the hide begins to be tensioned when immersed in the tanning bath, the stretching being stopped when tanning is performed.

In the annexed drawings:

Fig. 1 is a section on line I—I (Fig. 2).

Fig. 2 is a longitudinal section on line II—II (Fig. 1).

The apparatus comprises two jaws 1 and 2 to which the hide 3 is fixed by means of pins 4. Jaw 1 is pivotally fixed to a support 5; jaw 2 is also pivotably fixed to a U-shaped rod 6 which is guided through support 5. The latter is fixed by stays 7 to a vertical projection 7 integral with the bottom of the tank 8 adapted to contain the tanning bath. This tank also supports the reducing gear adapted to drive rod 6.

This gear comprises a driving shaft 9 provided with a driving pulley 10. Shaft 9, is provided with a worm 11 which meshes with a worm-wheel 12 keyed on an intermediate shaft 13. The latter is also provided with a worm 14 which meshes with a worm-wheel 15. Wheel 15 has a threaded hub which forms a nut on a threaded rod 16. The latter is connected with rod 6 at the upper end thereof.

Wheel 15 is laterally maintained by the casing 17 of the speed-reducing gear. One-

half of this casing is integral with tank 8.

The operation is as follows:

The hide is preferably cut into pieces somewhat wider than the belt to be obtained and as long as possible. Such a piece is disposed on the pivotable jaws 1 and 2 and the gear is actuated so that a slight initial tension is given to the hide.

The tanning bath 9 is then introduced into tank 8 up to a level somewhat above hide 3, and pulley 10 is continuously rotated at such a speed that, when the tanning operation is performed, the stretching of the hide is not dangerously high. The bath is then removed from the tank, the gear is rotated backwards until the piece of leather obtained is free and the latter is removed.

Owing to the progressive tension of the hide, the fibers are not suddenly stretched at the beginning of the tanning operation, when their elastic strength is low. The leather is nevertheless highly stretched which is an advantage well-known in the tanning industry. The leather obtained is highly elastic in the direction of the tension given during the tanning operation. The belts manufactured with such a leather do not substantially grow longer at use while being elastically stretchable.

I claim:

1. A process for the manufacture of leather for belts and the like, comprising the step of tanning a hide while progressively stretching it in one direction.

2. A process for the manufacture of leather for belts and the like, comprising the step of tanning a piece of hide substantially as wide as the belt to be finally obtained, while progressively stretching it in the direction of its length.

3. An apparatus for progressively and continuously stretching a piece of hide in one direction during the tanning operation, comprising a tank adapted to contain the tanning bath; a pair of jaws within said tank, adapted to receive the ends of the piece of hide; means to clamp said ends on said jaws; a rectilinearly movable rod to which one of said jaws is pivotably fixed; a support to which the other one of said jaws is pivotably

fixed; means to guide said rod; and means to drive said rod rectilinearly to tension said hide.

4. An apparatus as claimed in claim 3 wherein the means to drive the rod comprise a threaded rod fixed at the end of said first-named rod; a rotatable nut on said threaded rod; means to laterally maintain said nut; and a speed-reducing gear adapted to drive said nut.

10 In testimony thereof I affix my signature.
RENÉ CHAVAND.
